UNITED STATES PATENT OFFICE

LOUIS M. FABERO, OF CLEVELAND, OHIO, ASSIGNOR OF ONE-HALF TO E. C. BALZHISER,
OF CLEVELAND, OHIO

FUEL VAPORIZER

Application filed December 15, 1930. Serial No. 502,567.

This invention relates to fuel supply systems for internal combustion engines and has for an object the provision of a fuel vaporizer for preheating and vaporizing the liquid 5 fuel and mixing the same with air so as to provide a proper fuel mixture for the engine.

Another object of the invention is the provision of means for controlling the proportion of liquid fuel and air in accordance with 10 the speed of requirements of the engine.

Another object of the invention is the provision of a vaporizer in which the liquid fuel and air supply, the vaporizer and the controlling means are included in a single unit, 15 so that the invention may be readily installed, and will occupy a minimum amount of space.

With the above and other objects in view, the invention further includes the following 20 novel features and details of construction, to be hereinafter more fully described, illustrated in the accompanying drawings and pointed out in the appended claims.

In the drawings:

25 Figure 1 is a vertical sectional view of the invention.

Figure 2 is a section on the line 2—2 of Figure 1.

Figure 3 is a similar view on the line 3—3 30 of Figure 1.

Figure 4 is a section on the line 4—4 of Figure 2.

Figures 5 and 6 are detail sectional views 35 taken respectively on the lines 5—5 and 6—6 of Figure 1.

Figure 7 is a fragmentary view illustrating a slightly modified form of the invention.

Referring to the drawings in detail wherein like characters of reference denote corresponding parts, the reference character 10 indicates an outer casing which may be of any suitable size and shape and which accommodates an inner casing 11. This inner casing is spaced from the outer casing and provides, together with the latter, a heat circulating chamber 12 which surrounds the outside and top of the inner casing 11, while this inner casing provides a vaporizing chamber 13. The bottom 14 serves as a bottom 45 for both the outer and inner casings and this

bottom carries an annular flange 15 which extends upward into the bottom of the vaporizing chamber so as to hold the inner casing 11 in position. The bottom 14 is also provided with an annular flange 16 which receives the outer casing and provides means of attachment thereto as indicated at 17.

The heat circulating chamber is provided with an intake port 18 from which extends a nipple 19 and this nipple is adapted for 60 connection with a pipe 20 for the purpose of conducting the exhaust gases of the engine into the chamber. An outlet port 21 is provided for the vaporizing chamber and a nipple 22 extends from this port.

Extending upward from the top of the outer casing 10 is a sleeve or collar 23. This sleeve or collar provides a mixing chamber 24 which is cut off from the heat circulating chamber 12. The chamber 24 is provided 70 with oppositely located air intake ports 25 which are in communication with an air conduit 26 controlled by a valve 27. Extending into the mixing chamber 24 is a nozzle 28 which provides communication between this 75 chamber and the vaporizing chamber 13, the discharge end of the nozzle being an appreciable distance above the ports 25.

Located within the vaporizing chamber 13 are heat radiating drums 29 which are in 80 communication with the heat circulating chamber 12 through the medium of short pipes or nipples 30. Axially aligned nipples 31 extend from the outer casing 10 and are closed by threaded caps 32 so that by removing these caps access may be had to the interior of the drums 29.

Slidable axially within the mixing chamber 24 between the discharge end of the nozzle 28 and the air intake ports 25 is a hollow 90 valve 33. This valve operates over the nozzle 28 and for this purpose is provided with an opening 34 whose walls cooperate with a tapered nozzle 28 to cut off the supply of air from the mixing chamber or to regulate 95 the quantity of air admitted. This valve is operated from a shaft 35 through the medium of cams 36 and springs 37, the latter surrounding pins 38 which are attached to the valve. By reference to the drawings it will 100

be seen that the cams 36 act to force the valve downward so as to cut off or reduce the quantity of air admitted through the ports 25, while the springs 37 act to move the valve upward to increase the amount of admitted air when the shaft 35 is rotated in one direction. Movement of the shaft in opposite directions is controlled through the medium of adjustable stops 39 and an arm 40 mounted upon the shaft 35. An arm 41 also secured to the shaft 35 provides means for connection with a suitable operating lever for the purpose of rocking the shaft 35. The mixing chamber is adapted for communication with the intake manifold of the engine.

Extending downwardly from the bottom 14 of the casing is a float chamber 42 having a float controlled valve 43 to regulate the admission of liquid fuel into the chamber, a pipe 44 extending from a suitable source of liquid fuel supply for this purpose. A pipe 45 extends from and is in communication with the float chamber and has extending therefrom nozzles 46 and 47. These nozzles provide communication between the pipe 45 and the vaporizing chamber. The amount of fuel passing through the nozzle 46 is controlled by a needle valve 48 which is adjusted to supply the proper amount of liquid fuel for ordinary speed and loads. The nozzle 47 is controlled by a needle valve 49 which is adjusted to normally close the said nozzle and prevent the passage of fuel. This needle valve however is carried in a slidingly mounted sleeve 50 so that by moving the valve axially communication may be established between the pipe 45 and the interior of the vaporizing chamber. A lever 51 which is pivotally mounted as shown at 52, has one end pivotally secured to the sleeve 50, while the opposite end of the lever has a pivotal connection with a rod 53. This rod is pivotally connected with an arm 54 carried at one end of the shaft 35. The rod 53 is of sectional formation and the sections are adjustably connected by means of a coupling 55 so that the length of the rod may be adjusted to regulate the degree of opening of the needle valve 49. Opening movement of the valve is yieldingly resisted by a spring 56.

Instead of having the valve 49 extend diametrically through the pipe 45, the said pipe 45 may be provided with a partition 57 having a port 58 therein. This partition is located between the nozzles 46 and 47 and the port is controlled by a needle valve 59 which is threadedly adjustable in the sleeve 60. This sleeve is threadedly adjustable into the end of the pipe 45 and carries an arm 61 which extends diametrically therefrom and its pivotal connection with the rod 53. The outer end of the sleeve 60 is toothed as shown at 62 for engagement with the teeth on a collar 63. This collar is slidable axially upon the valve

59 and outward sliding movement is yieldingly resisted by means of a spring 64 which is located between the end of the collar and the finger piece 65 at the outer end of the valve.

Normally the valve will be adjusted to close the port 58, and when the load or speed of the engine increases, this valve will be opened proportionate to the degree of opening of the valve 33.

Normally, fuel from the chamber 42 enters the vaporizing chamber through the injector nozzle 46 and as the valve 33 is partly open, the upward rush of air will create a vacuum or suction through the vaporizing chamber so as to draw this fuel upward. In its upward movement the raw fuel will strike the heat radiating drums 29 and the walls of the inner casing 11 and will be thoroughly broken up and vaporized. As the vaporized liquid fuel passes into the mixing chamber 24 it will be mixed with air drawn inward through the ports 25, so that this fuel mixture will be forced into the intake manifold and will enter the cylinders of the engine in a preheated and thoroughly vaporized state.

When the load upon the engine or the speed is increased, the shaft 35 will be rocked, which will simultaneously open the valve 33 and the valve 49, so that both the liquid fuel and air supply will be increased.

By arranging the air conduit 26 in the manner shown, air will also be heated before it is mixed with the liquid fuel vapor.

The invention is susceptible of various changes in its form, proportions and minor details of construction and the right is herein reserved to make such changes as properly fall within the scope of the appended claims.

Having described the invention what is claimed is:—

1. A fuel vaporizer comprising spaced outer and inner casings forming a heat circulating chamber therebetween coextensive with the sides and top thereof, means for conveying exhaust gases into the heat circulating chamber, means for delivering the exhaust gases from said chamber, a mixing collar rising centrally from the outer casing and having an air conduit thereto and opening into the same at opposite sides thereof, a nozzle rising from the inner casing into the mixing collar, superposed heat drums in the inner casing and opening into the heat circulating chamber, a hollow valve slidable axially in the mixing collar between the end of the nozzle and the communication of the air conduit with said collar, and float valve controlled fuel inlet means communicating with the inner casing remote from the nozzle.

2. A fuel vaporizer comprising spaced outer and inner casings forming a heat circulating chamber therebetween coextensive with the sides and top thereof, means for conveying exhaust gases into the heat circulating

chamber, means for delivering the exhaust gases from said chamber, a mixing collar rising centrally from the outer casing and having an air conduit thereto and opening into the same at opposite sides thereof, a nozzle rising from the inner casing into the mixing collar, superposed heat drums in the inner casing and opening into the heat circulating chamber, a hollow valve slidable axially in the mixing collar between the end of the nozzle and the communication of the air conduit with said collar, float valve controlled fuel inlet means communicating with the inner casing remote from the nozzle, and a regulating valve for the fuel inlet means.

3. A fuel vaporizer comprising spaced outer and inner casings forming a heat circulating chamber therebetween coextensive with the sides and top thereof, means for conveying exhaust gases into the heat circulating chamber, means for delivering the exhaust gases from said chamber, a mixing collar rising centrally from the outer casing and having an air conduit thereto and opening into the same at opposite sides thereof, a nozzle rising from the inner casing into the mixing collar, superposed heat drums in the inner casing and opening into the heat circulating chamber, a hollow valve slidable axially in the mixing collar between the end of the nozzle and the communication of the air conduit with said collar, float valve controlled fuel inlet means communicating with the inner casing remote from the nozzle, a regulating valve for the fuel inlet means, and connections between the hollow valve and the last named valve.

In testimony whereof I affix my signature.

LOUIS M. FABBRO.
